STAPLING DEVICE

Joseph Leibowitz, Brooklyn, N. Y.

Application January 9, 1953, Serial No. 330,509

10 Claims. (Cl. 1-3)

1

The present invention relates to stapling devices.

It is more directed to a hand stapling device of the electrically powered type.

The particular embodiment of the present invention, is illustrated in the drawings and which will be described hereinafter in greater detail, comprises generally, a magazine, a housing on the magazine, a plunger mounted in the housing and electro-magnetic means for effecting movement of the plunger.

It is a principal object of the present invention to provide a simple and efficient stapling device which is operated by electric power and which eliminates the tiring hand punching and squeezing operations heretofore required.

It is another object of the present invention to provide a stapling device of the type described which utilizes magnetic force for driving the staples.

It is still another object of the present invention to provide a stapling device of the type described which requires a minimum number of parts, which parts are adapted to be stamped or otherwise mass produced and which may be quickly and easily assembled.

It is still another object of the present invention to provide a stapling device of the type described, wherein a novel housing structure having depending wall extensions is combined with an open ended magazine to form a staple outlet throat.

It is yet another object of the present invention to provide a stapling device of the type described having a novel plunger guide which extends upwardly into the plunger and constrains the latter to up and down movement.

It is a further object of the present invention to provide a stapling device of the type described which is simple and durable, effective for its intended objects, and which is adapted to be manufactured and sold at a reasonable cost.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention:

Fig. 1 is a longitudinal sectional elevational view of a stapling device constructed in accordance with the present invention;

2

Fig. 2 is a sectional view taken on the line 2-2 of Fig. 1;

Fig. 3 is an enlarged fragmentary view of the device as shown in Fig. 1, with the plunger in its downward position;

Fig. 4 is a sectional view taken on the line 4-4 of Fig. 3.

Referring now more particularly to the drawings, the embodiment of the invention illustrated therein comprises a base 10, having depending side walls 11 and 12, which are connected by a web or top wall 13. The side walls 11 and 12 have their lower edges 14 and 15 adapted to rest upon a horizontal supporting surface (not shown).

On the upper surface of the top wall 13 adjacent one end 16 is secured, by welding or other suitable means, an anvil 17 for receiving and turning in the ends of a driven staple. Adjacent 20 the other end 18 of top wall 13 are a pair of laterally spaced upstanding ears 19.

Arranged longitudinally of and in spaced overlying relation with respect to the base 10 is a magazine 20 comprising generally a magazine frame 21 and a magazine rail 22 disposed longitudinally of and within the magazine frame. The magazine frame 21 comprises a bottom wall 23 from which extend upwardly side walls 24 having inwardly extending flanges 25 adjacent their upper edges. The frame 21 is provided with a pair of laterally spaced depending ears 26 adjacent to and spaced inwardly from one end 27 of the frame. The ears 26 are each disposed in side by side relation with respect to one of the ears 19, and a pin 28 extends through the ears 19 and 26 to pivotally mount the magazine 20 for rotative movement about the pin, and space the frame 21 above the base 10.

The magazine rail 22 (Fig. 4) comprises a horizontal top wall 29 from which extend downwardly side walls 30. The top wall 29 is spaced below the flanges 25 and the side walls 30 are spaced inwardly of the side walls 24, providing space for the staples 31 which slide on the rail 22 between said rail and the frame 21. The rail 22 and frame 21 have their ends open, to thereby form an open ended magazine adapted to receive staples at one end 27 and discharge staples at the other end 32.

Disposed on the flanges 25, spaced inwardly from the magazine end 32 and spaced inwardly from the magazine side walls 24 is a plunger guide 33 having front and rear walls 34 and 35, side walls 36, and a top wall 37. The side walls 36 are formed with depending lugs 38 which extend into the flanges 25 and are fixedly secured therein

by any suitable means. Thus, the plunger guide 33 is substantially an upstanding box-like member spaced inwardly from the side walls 24 and end 32 of the magazine 20.

Disposed over and enclosing the plunger guide 33 is a housing or body 40 having a front wall 41, a rear wall 42, and side walls 43. The front wall 41 is recessed forwardly as at 44, and provided with a depending wall extension 45 spaced from the end 32 of staple magazine 20, for a purpose appearing hereinafter. The side walls 43 are provided with depending side wall extensions 46 which are secured to the outer sides of magazine frame side walls 24 by any suitable means, such as welding (not shown). In this manner, the housing 40 is fixedly secured in upstanding position on the magazine 20. The depending side wall extensions 46 extend forwardly beyond the end 32 of the magazine 20 and merge into the depending front wall extension 45, the depending front and side wall extensions combining with the end 32 to provide an outlet throat 47 for the staples in the magazine. The rear housing wall 42 is provided with a rearwardly extending hollow lug 48 having side walls 49 and a bottom opening 50, all for a purpose appearing hereinafter.

The upper portion of housing 40 is enlarged as at 51, the front and rear walls 41 and 42 being formed with outwardly extending portions 52 and 53, and the side walls 43 being formed with outwardly extending portions 54. The enlarged housing portion 51 is formed of upstanding front and rear walls 55 and 56 on the laterally extending portions 52 and 53, respectively. Similarly, the laterally extending side wall portions 54 are provided with upstanding outwardly offset side wall portions 57 adjacent the outer edges of portions 54. The front and rear wall portions 55 and 56 terminate in upper edges 58 and 59, and the side wall portions 57 terminate in upper edges 60. Thus, the housing 40 has its upper end open, for a purpose to be described hereinafter. The rear wall portion 56 is provided with a rearwardly extending tubular portion 61 having its rearward end open, as at 62, and formed with an opening 63 adjacent to and spaced rearwardly from the wall portion 56.

Disposed within the hollow lug 48 and extending between the side walls thereof 49 is a pin 64 having a resilient strip 65 wound about the pin and having its free end connected to the staple pusher 66. The staple pusher 66 includes a plate 67 slidably mounted on the rail 22 and having its end 68 engageable with the rearmost staple in the magazine 20. The staple pusher 66 is resiliently urged forwardly by the action of strip 65 to feed the forwardmost staple into the staple throat 47.

Slidably receiving the plunger guide 33 is the plunger 70, which comprises front and rear walls 71 and 72, respectively, and side walls 73 extending between the front and rear walls. A top wall 74 extends between the front and rear walls 71 and 72, and the side wall 73. The plunger 70 has its lower end open and slidably receives therethrough the plunger guide 33. Thus, the plunger front wall 71 is slidable in the space between the plunger guide front wall 34 and housing front wall 41, and the plunger rear wall 72 is slidable between the plunger guide rear wall 35 and housing rear wall 42. Similarly, the plunger side walls 73 are slidable in the space between plunger guide side walls 36 and housing side walls 43. Secured in partially overlapping relation with

respect to the plunger front wall 71 and depending therefrom is a blade 75 which has its upper end secured to the plunger front wall by rivets 76 and which has its lower end 77 movable into the staple outlet throat 47. Thus, the lower end 77 of blade 75 will drive the forwardmost staple 31 outwardly through the staple outlet throat 47 and against the anvil 17 to secure the sheets or other material 78 disposed between the magazine frame 21 and anvil 17. The rivets 76 will ride freely with the plunger 70 and blade 75 as their heads extend into the recessed front wall portion 44.

In order to normally retain the blade 75 out of the staple outlet throat 47, a compression coil spring 80 is disposed within the plunger 70, having its upper end 81 abutting the underside of plunger top wall 74 and having its lower end 81 abutting the upper side of top wall 37 of plunger guide 33.

On the upper side of top wall 74 of plunger 70 is fixedly secured, by any suitable means, a U-shaped member 85 having upstanding legs 86 and 87. Disposed within the enlarged upper portion 51 of housing 40 is a solenoid coil 90 which is mounted on brackets 91, the latter being secured to the laterally extending portions 52, 53 and 54 by rivets 92. The solenoid coil 90 has a central through opening in alignment with the plunger 70, and is provided with lead posts 93 and 94, adjacent the tubular rearward extension 61. Extending slidably through the solenoid coil 90 and in vertical alignment with the plunger 70 is a magnetic core, of conventional laminated structure, and designated 100. The core 100 is provided with a depending lug 101 which extends between the legs 86 and 87 of U-shaped member 85, and is secured thereto by a pin or rivet 102. Thus, the core 100 and plunger 70 are connected together for simultaneous movement toward and away from the magazine 20 for effecting discharge of a staple through the staple outlet throat 47, as heretofore described.

The upper end of housing portion 51 is provided with a cover 105 having front and rear wall portions 106, side wall portions 107, a top wall 108 and laterally extending front and rear portions 109. The laterally extending portions 109 seat on the upper edges 58 and 59 of front and rear wall portions 55 and 56, and the side wall portions 107 rest upon the upper edges 60 of side wall portions 57. The cover may be secured to the housing portion 51 by any suitable means.

Connected to the terminal posts 93 and 94 are wires 110 and 111 which extend outwardly through the aperture 62 to a source of electric current (not shown). Interposed in the line 110 is a switch 112, which is mounted in the opening 63 by securing means 113, and is preferably of the easily manipulated button type. The opening 62 may be provided with a yieldable gasket or washer 114 to minimize wear on the electric wires.

In operation, the staple pusher 66 is removed from the rail 22 by sliding outwardly beyond the end 27 of magazine 20 against the force of resilient strip 65. A supply of staples may then be inserted into the magazine through end 27 and slid along the rail 22. The pusher 66 is then inserted into the magazine and resiliently holds the supply of staples against the front wall depending extension 45, the forwardmost staple being within the staple outlet throat 47. By holding the tubular extension 61 with the hand of the operator, the magazine 20 may be swung

upwardly about the pin 28 and material to be fastened may be inserted between the anvil and magazine, and the magazine returned to its position of movement toward the base 10. With the hand of the operator still on the tubular portion 61, the switch 112 may be closed to actuate the solenoid 30 and effect a magnetic field through the core 100 to force the core toward the magazine 20. The core 100 and plunger 70 will move toward the magazine 20 against the force of spring 80, see Fig. 3, the plunger being guided by the plunger guide 33 and the blade 75 extending into the staple outlet throat 47 for driving a staple into the material 78, as heretofore described. It is appreciated that the stapling device of the present invention may also be used as a tacker. This may be accomplished by removing the base 10, which modification is within the scope of the present invention.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A stapling device comprising a base, an anvil on one end of the base, an open ended staple magazine overlying said base with one end adjacent to said anvil and pivoted to said base at a point spaced from said anvil, an upstanding housing on said magazine adjacent said one end thereof, means on said housing and combining said magazine to form a staple outlet throat, a plunger in said housing, means mounting said plunger for sliding movement toward and away from said magazine, resilient means urging said plunger away from said magazine, a blade carried by said plunger and movable into said throat for ejecting a staple from said magazine against said anvil, a magnetic core disposed within said housing above said plunger and connected to the latter for movement therewith toward and away from said magazine, and electro-magnetic means for effecting movement of said core toward said magazine against the force of said resilient means, said electro-magnetic means being adapted for connection to a source of electric current.

2. A stapling device as in claim 1 in combination with a hand grip on said housing, and a hand actuatable switch on said hand grip for effecting the passage of current through said electro-magnetic means.

3. A stapling device comprising a base, an anvil on one end of the base, an open ended staple magazine overlying said base with one end adjacent to said anvil and pivoted to said base at a point spaced from said anvil, an upstanding housing on said magazine adjacent said one end thereof, means on said housing and combining said magazine to form a staple outlet throat, a plunger in said housing, means mounting said plunger for sliding movement toward and away from said magazine, resilient means urging said plunger away from said magazine, a blade carried by said plunger and movable into said throat for ejecting a staple from said magazine against said anvil, a magnetic core disposed within said housing above said plunger and connected to

the latter for movement therewith toward and away from said magazine, and electro-magnetic means for effecting movement of said core toward said magazine against the force of said resilient means, said electro-magnetic means being adapted for connection to a source of electric current, said electro-magnetic means comprising a solenoid coil circumscribed about said core and adapted to produce a magnetic field through said core for moving the latter toward said magazine.

4. A stapling device comprising a base, an anvil on one end of the base, an open ended staple magazine overlying said base with one end adjacent to said anvil and pivoted to said base at a point spaced from said anvil, an upstanding housing on said magazine adjacent said one end thereof, means on said housing and combining said magazine to form a staple outlet throat, a plunger in said housing, means mounting said plunger for sliding movement toward and away from said magazine, resilient means urging said plunger away from said magazine, a blade carried by said plunger and movable into said throat for ejecting a staple from said magazine against said anvil, a magnetic core disposed within said housing above said plunger and connected to the latter for movement therewith toward and away from said magazine, and electro-magnetic means for effecting movement of said core toward said magazine against the force of said resilient means, said electro-magnetic means being adapted for connection to a source of electric current, said first named means comprising a pair of depending wall extensions on opposite sides of said magazine and extending outwardly beyond said one end thereof, and a depending wall extension in facing spaced relation with respect to said one end of said magazine and extending between said pair of depending wall extensions, whereby said one end of said magazine and said depending wall extensions combine to form a staple outlet throat.

5. A stapling device comprising a base, an anvil on one end of the base, an open ended staple magazine overlying said base with one end adjacent to said anvil and pivoted to said base at a point spaced from said anvil, an upstanding housing on said magazine adjacent said one end thereof, means on said housing and combining said magazine to form a staple outlet throat, a plunger in said housing, means mounting said plunger for sliding movement toward and away from said magazine, resilient means urging said plunger away from said magazine, a blade carried by said plunger and movable into said throat for ejecting a staple from said magazine against said anvil, a magnetic core disposed within said housing above said plunger and connected to the latter for movement therewith toward and away from said magazine, and electro-magnetic means for effecting movement of said core toward said magazine against the force of said resilient means, said electro-magnetic means being adapted for connection to a source of electric current, said plunger mounting means comprising a member positioned in spaced relation within said housing and fixedly secured on said magazine, said member extending upwardly into said plunger and slidably received therein, to thereby mount said plunger for sliding movement toward and away from said magazine.

6. A stapling device as in claim 5, wherein said resilient means comprises a compression spring within said plunger having one end bearing

against said member and the other end bearing against said plunger.

7. A stapling device comprising an open ended staple magazine, an upstanding housing on said magazine adjacent one end thereof and forming therewith a staple outlet throat, a plunger mounted in said housing for movement toward and away from said magazine, resilient means urging said plunger away from said magazine, a blade carried by said plunger and movable into said throat for ejecting a staple from said magazine, a magnetic core disposed within said housing above said plunger and connected to the latter for movement therewith toward and away from said magazine, and electro-magnetic means for effecting movement of said core toward said magazine against the force of said resilient means, said electro-magnetic means being adapted for connection to a source of electric current.

8. A stapling device as in claim 7, in combination with a hand grip on said housing, and a hand actuatable switch on said hand grip for effecting the passage of current through said electro-magnetic means.

9. A stapling device comprising an open ended staple magazine, an upstanding housing on said magazine adjacent one end thereof and forming therewith a staple outlet throat, a plunger mounted in said housing for movement toward and away from said magazine, resilient means urging said plunger away from said magazine, a blade carried by said plunger and movable into said throat for ejecting a staple from said magazine, a magnetic core disposed within said

35

housing above said plunger and connected to the latter for movement therewith toward and away from said magazine, and electro-magnetic means for effecting movement of said core toward said magazine against the force of said resilient means, said electro-magnetic means being adapted for connection to a source of electric current, said electro-magnetic means comprising a solenoid coil circumscribed about said core and adapted to produce a magnetic field through said core for moving the latter toward said magnet.

10. A stapling device comprising an open ended staple magazine, an upstanding housing on said magazine adjacent one end thereof and forming therewith a staple outlet throat, a plunger mounted in said housing for movement toward and away from said magazine, resilient means urging said plunger away from said magazine, a blade carried by said plunger and movable into said throat for ejecting a staple from said magazine, a magnetic core disposed within said housing above said plunger and connected to the latter for movement therewith toward and away from said magazine, and electro-magnetic means for effecting movement of said core toward said magazine against the force of said resilient means, said electro-magnetic means being adapted for connection to a source of electric current, said resilient means comprising a compression spring disposed within and bearing against said plunger for urging the latter away from said magazine.
